[57] CLAIM

The ornamental design for a body squeegee, as shown and described.

DESCRIPTION

FIG. 1 is a side elevational view showing my design of a body squeegee;

FIG. 2 is an edge elevational view showing the left edge of FIG. 1;

FIG. 3 is a elevational view of the opposite side of FIG. 1; and,

FIG. 4 is a section on line 4—4 of FIG. 1.

The undisclosed sides of the squeegee are unornamented and follow the contours of the sides shown.

FIG. 4

FIG. 1

FIG. 2

FIG. 3
